(57) **CLAIM**

I claim the ornamental design for a one person vehicle, as shown and described.

DESCRIPTION

FIG. 1 is a perspective view of the one person vehicle with the arms carrying the wheels in an unfolded position.

FIG. 2 is another perspective view of the one person vehicle with the arms carrying the wheels in a folded position.

FIG. 3 is a side elevation view of the one person vehicle with the arms carrying the wheels in an unfolded position, the opposite side view being a mirror image thereof;

FIG. 4 is a side elevation view of the one person vehicle with the arms carrying the wheels in a folded position, the opposite side view being a mirror image thereof;

FIG. 5 is a front elevation view of the one person vehicle with the arms carrying the wheels in an unfolded position, the rear elevation view being a mirror image thereof;

FIG. 6 is a front elevation view of the one person vehicle with the arms carrying the wheels in a folded position, the rear elevation view being a mirror image thereof;

FIG. 7 is a top plan view of the one person vehicle with the arms carrying the wheels in an unfolded position.

FIG. 8 is a top plan view of the one person vehicle with the arms carrying the wheels in a folded position.

FIG. 9 is a bottom view of the one person vehicle with the arms carrying the wheels in an unfolded position.

FIG. 10 is a bottom view of the one person vehicle with the arms carrying the wheels in a folded position.

FIG. 11 is a bottom perspective view of the one person vehicle with the arms carrying the wheels in an unfolded position; and,

FIG. 12 is a bottom perspective view of the one person vehicle with the arms carrying the wheels in a folded position.
